UNITED STATES PATENT OFFICE.

EDNA J. CABLE, OF CHAFFEE, MISSOURI.

RAILWAY GATE AND SIGNAL.

Application filed May 27, 1926. Serial No. 112,013.

My invention relates to gates and railway signals, and especially to that type in which the signal is automatically changed when the gate is opened and closed.

5 The primary object of my invention is to provide a combined gate and signal device of such a nature that the signal will be automatically changed when the gate is either opened or closed.

10 It is further required that when a train from the junior road is crossing the tracks of the senior road that the gate shall be locked across the tracks of the senior road.

The law further specifies that suitable signals be provided to indicate the position of 15 the gate, which said signals usually consist of different colored lights for use when the visibility is low and at night, and certain types of painted boards for use during the 20 daylight.

It frequently happens that the flagman who opens the gate neglects to change the signals at the same time, with the result that serious accidents have occurred.

25 In order to prevent such occurrences, I have devised a simple and effective means by which the signals automatically change with the opening and closing of the gate, so that it is impossible for the gate to be opened 30 without the proper signal showing at the proper place.

Other objects and advantages of my invention will be disclosed in the following specification, claim and drawings, in 35 which:

Fig. 1 illustrates the application of my combined railway gate and signal, showing the gate locked open for free passage of a train on the main line; and, also, shows the 40 vertically disposed arms of the signal indicating a clear track in both directions.

Fig. 2 shows that the track illustrated in Fig. 1 is closed and both the vertically disposed signal arms and the horizontal signals indicate that the track is closed.

45 Fig. 3 is a detailed view of the automatic locking device.

Fig. 4 shows in detail the manner in which the locking device may be secured by 50 padlock.

Fig. 5 illustrates the manner in which the rotatable signal is hinged and supported against downward movement by a shoe.

55 My invention consists of a standard 1, hingedly connected to a vertically disposed post 2, firmly set in the ground at the apex

of the angle formed by two railways crossing each other. Rigidly attached at right angles to the standard 1 is a gate or signal bar 3.

60 On the opposite side of the railroad tracks from the post 2, shorter posts 4 and 5 are firmly set in the ground, thus it is obvious that when the tracks cross at right angles the posts 4 and 5 will be disposed 90 deg. apart, 65 and the post 2 will be in the circle of the circle which would be inscribed by the rotation of the gate or bar 3.

As the gate must be normally locked across 70 the junior road, the post 4 is provided with a suitable locking mechanism, shown in detail in Fig. 4.

75 On the post 5 is a gravity locking mechanism shown in detail in Fig. 3, which serves the purpose of holding the gate or bar 3 securely in position while the train of the junior road is crossing the tracks of the senior road.

At the upper end of the standard 1, a signal lamp 6 is provided, the two opposite 80 sides of which show one color light, and the two other opposite sides show a different color light.

The standard 1 is, also, provided at its 85 upper end with four signal arms, two of which 7 and 8 are permanently disposed in a horizontal position, the other two 9 and 10 being permanently disposed in a vertical position.

90 The horizontal arms 7 and 8 are painted with the usual signal colors, in such a manner that they will always indicate whether the road is clear or closed by reason of the fact that the horizontal bar 3 and the standard 1 are rigidly hinged, as shown in Fig. 5, and when the bar 3 is moved from post 4 95 to post 5, or reversed, the signal will automatically be moved or reversed.

An automatic locking device 11 is pivotally joined to the post 5 at 12, so that the locking portion 13 of the device normally rests on top of the post 5 by means of its weight. Its outer end is curvilinear in outline and of such shape that when the bar 3 is swung against it the latch 13 is raised, permitting the bar to be held by the hooked portion 14. Rigidly attached to the top of the post 4 is a locking device, so designed that when the bar 3 is swung against it, it automatically closes the latch 15, one end of which engages a slotted portion, not shown, 110 in the upright standard 16.

An eye 17 is provided in the upper por-

tion of the latch 15 through which the hook of a padlock 18 can be inserted and locked in place, thereby securely holding the gate in position across the junior tracks.

5 The standard 1 is pivotally hinged to the post 2 by means of latches 19 and 20. A metal shoe 21 is provided with a suitable opening on its upper surface to receive the toe of the standard 1, thereby preventing the 10 weight of the gate and standard from causing the hinges to sag or become unduly worn.

Having fully described my invention and its method of operation and construction, what I claim as new and useful, and desire 15 to secure by Letters Patent is:—

A combined railway gate and signal of the class described, comprising a vertical, rotatable standard hingedly supported by a post embedded in the ground in a vertical 20 position adjacent a railroad track and adapted to rotate through 90 degrees, a plurality of signal arms rigidly attached to the upper end of said rotatable standard, two of which are diametrically opposite each other in a 25 horizontal plane, and two others being disposed in a vertical plane 90 degrees from the

horizontally disposed signal arms, a signal lantern attached to the center of the upper end of said rotatable standard and having four plain sides, two opposite sides of which 30 are enclosed with glass of one color and the two alternate and opposite sides being enclosed by glass of a different color, means for internally illuminating said lantern, a horizontally disposed bar or gate rigidly attached to said standard, posts rigidly embedded in the ground 90 degrees apart on each side of a railway track at equal distances from said rotatable standard, automatic locks rigidly affixed to said posts 35 adapted to engage and lock said bar or gate when swung with force against said locks, means for securely locking one of said locks against accidental or intentional release by the use of an ordinary padlock, means for 40 supporting the weight of said standard and said gate against vertical movement.

In witness whereof I have hereunto affixed my signature this 17 day of April, 1926.

EDNA J. CABLE.
